UNITED STATES PATENT OFFICE.

WILLIAM C. GEER, NEWTON S. NOBLE, AND EARL S. TEED, OF AKRON, OHIO,
ASSIGNORS TO THE B. F. GOODRICH COMPANY, OF NEW YORK, N. Y., A COR-
PORATION OF NEW YORK.

GAS-MASK.

1,371,236.

Specification of Letters Patent. Patented Mar. 15, 1921.

Application filed November 7, 1918. Serial No. 261,442.

To all whom it may concern:

Be it known that we, WILLIAM C. GEER, NEWTON S. NOBLE, and EARL S. TEED, citizens of the United States, residing at Akron, 5 in the county of Summit and State of Ohio, have invented a certain new and useful Gas-Mask, of which the following is a specification.

This invention relates to the construction 10 of gas masks and respirators, and its principal object is to provide improved sealing means for the breathing chamber and other parts.

Of the accompanying drawings, 15 Figure 1 is a side elevation, partly in section, showing a gas mask constructed according to our invention, applied to a man's head.

Fig. 2 is a rear elevation, omitting parts 20 of the head straps.

Fig. 3 is a horizontal section on the line 3—3 of Fig. 2.

Fig. 4 is a view similar to Fig. 1 showing 25 a modification.

Fig. 5 is a rear elevation of said modification.

Referring at first to Figs. 1 to 3, 10 is a face cover adapted to be made of any suitable material such as rubber or rubberized 30 fabric and provided with straps 11, 12, 13 forming a head harness. 14, 14 are the eye-pieces comprising suitable frames and lenses, and 15 is a nozzle formed integrally with the body of the face cover and inclosing a relatively-small breathing chamber 16. In side connection with this chamber is an inhaling pipe 17 (Fig. 3) leading to the air filter (not shown), and in the bottom wall thereof is an outlet 18 provided with the usual ex- 35 haling valve 19.

The outline of chamber 16, when viewed from the rear, as in Fig. 2, is substantially triangular or pear-shaped, and around its rear opening are located suitable free-edged, 40 flexible, soft-rubber packing lips or gaskets, which, as here shown, project laterally both inwardly and outwardly of the chamber, 20 being the inwardly-projecting lip completely surrounding the rear opening of 45 the chamber, whose apex is on the bridge of the nose, and 21, 21 being two similar, outwardly-projecting lips located at the sides of the chamber and merging with a similar, 50 flexible packing lip or flap 22 which surrounds both of the eye-pieces 14. The inner

flap 20 seals the chamber 16 when the wearer exhales, and the outer flaps 21, 22 seal it when he inhales, the combination of the two providing effectively for both conditions. The marginal portion of the covering 10, 60 which acts only imperfectly to seal the mask because it cannot readily be made to conform accurately to different wearers, is therefore not relied upon as much as in other masks. 65

The provision of the relatively-small breathing chamber 16 greatly reduces the dead-air space as compared with masks which are sealed only by the margins of the face cover. This renders breathing easier 70 and also reduces the fogging of the eye-piece lenses by condensed breath moisture. The flexible lips 20 and 21 promote the sealing of this chamber by conforming to the wearer's face, and the lip or flap 22 performs a 75 similar function for the spaces in front of the wearer's eyes.

The embodiment shown in Figs. 4 and 5 differs specifically from the foregoing in the use of a structurally-separate nozzle 15^a 80 containing the breathing chamber 16^a and mounted within the main face cover 10^a, to the front portion of which it is attached by means of the breathing fixture 23 which carries the inhaling pipe 17 and the exhaling 85 valve 19. The nozzle 15^a is further supported from the margin 24 of the face cover by means of straps 25, 26 which hold its rear edge against the wearer's face. The inwardly and outwardly directed packing lips 90 are shown at 20^a and 21^a, and the lower margin of the nozzle in this instance underlies the wearer's chin instead of his lower lip. In this case the packing flap surrounding the eye-pieces 14 is omitted. A pair of 95 free-edged, depending flaps 27 are provided at the two upper corners of the face cover to increase the sealing effect at these points, their function being broadly similar to that of the flexible packing flaps previously described. 100

Various other changes may be made without departing from the scope of our invention, and it will be understood that the invention is not wholly limited to a respirator 105 employing eye-pieces.

We claim:

1. In a respirator, the combination of a nose and mouth covering chamber having inhaling and exhaling passages, an auto- 110

matic valve controlling the exhaling passage, and free-edged, face-engaging, flexible flaps around the margin of said chamber, projecting inwardly and outwardly, for substantially sealing the interior of said chamber at said margin, during both inhaling and exhaling.

2. A gas mask comprising a face cover having eye-pieces, a relatively-small breathing chamber in front of the nose and mouth,

and a flexible, free-edged, face-engaging sealing flap surrounding the eye-pieces and extended downwardly at the sides of said chamber.

In testimony whereof we have hereunto set 15 our hands this 4th day of November, 1918.

WILLIAM C. GEER.
NEWTON S. NOBLE.
EARL S. TEED.
